DESIGN FOR A DESK

Paul M. Fuller, Chicago, Ill., assignor to Clemco
Desk Mfg. Co., Chicago, Ill., a corporation of Illinois

Application January 30, 1937, Serial No. 67,355

Term of patent 7 years

To all whom it may concern:

Be it known that I, Paul M. Fuller, a citizen of the United States and residing at Chicago, county of Cook, and State of Illinois, have invented a new, original, and ornamental Design for Desks, of which the following is a specification, reference being made to the accompanying drawings, forming a part thereof.

Fig. 1 is a front perspective view of the desk, showing my new design;

Fig. 2 is a rear perspective view, and

Fig. 3 is a top plan view thereof.

I claim:

The ornamental design for a desk substantially as shown.

PAUL M. FULLER.
